UNITED STATES PATENT OFFICE.

JOSEF SAVOIE, OF CENTRAL FALLS, RHODE ISLAND.

PAPER-CAP REMOVER.

1,105,210.

Specification of Letters Patent. Patented July 28, 1914.

Application filed February 13, 1914. Serial No. 818,592.

To all whom it may concern:

Be it known that I, JOSEF SAVOIE, a citizen of the United States, residing at Central Falls, in the county of Providence and 5 State of Rhode Island, have invented a new and useful Improvement in Paper-Cap Removers, of which the following is a specification.

This invention relates to certain new and 10 useful improvements in paper cap removers, and relates particularly to a remover used in connection with the usual pasteboard cap or disk employed to close the mouths of milk bottles, and the like.

15 The primary object of the invention is to provide a remover which is made of a single piece of wire, and which in its construction is simple and involves a minimum of material which can be easily fashioned or formed 20 into the completed article.

Further, the invention aims to provide a remover which is capable of being easily and quickly applied to the cap and operated to remove the latter.

25 In the drawings Figure 1 is a perspective view of a fragment of a bottle showing the present invention applied to the cap thereof in position for removing the latter. Fig. 2 is a top plan view of the invention. Fig. 3 30 is a side elevation.

The entire device is formed of a single strand of wire which is doubled over intermediate its ends at 1 to provide a pair of spaced and preferably parallel members 2 35 and 3, the latter conjointly providing a handle for the article, by means of which the same may be manipulated.

The end portion of the member 3 is bent outwardly on one side thereof at an incline 40 at 4 and is then bent inwardly and across member 3 and terminates at a point on the opposite side of member 3 to provide a transverse bearing arm 5, which latter is preferably bowed downwardly at its center 45 to guide the movement of the arm 5, when the latter is being moved into engagement with the disk or cap C of the bottle or jar. The arm 5 is then inwardly extended at an incline toward the member 3, as indicated at 50 6 and terminates at the inner end of said member 3, where it is secured by solder. The parts 4 and 6 are thus seen to provide side arms which connect the transverse arm 5 to the member 3, the arms 4, 5 and 6, forming 55 a triangle.

The free end portion of the member 2 is bent downwardly at an incline at 7 and is sharpened to provide a point 8 which latter will readily enter or penetrate the disk C. The inclined point bearing portion of member 2 extends over the joint formed between the free end of the side arm 6 and the member 3, and is soldered at said joint, the soldering of the three parts 3, 6 and 7, being performed in one operation. The point 8 extends beneath the transverse arm 3 and terminates in a vertical plane adjacent thereto. The inclined portion 7 provides a ready and convenient seat for the thumb or forefinger of the operator, as is evident.

In operation, the transverse arm is brought to seat upon or engage with the top edge of the milk jar or bottle, the handle being held in substantially vertical position so that upon downward movement of the handle at 75 its outer end, the point 8 will penetrate or engage in the disk C, whereby the latter will be raised up out of engagement with the bottle in an obvious manner.

It is particularly to be noted that the 80 device constructed as herein described and shown in the drawings, involves a minimum of bending operations, which is a desideratum in that it enables corresponding minimum of machinery cost to produce the articles in large quantities.

Having thus described my invention, I claim as new and desire to secure by Letters Patent:

1. In a bottle paper cap remover, a section of wire bent to form a handle which has substantially parallel members, the lower of said members being extended outwardly at an incline on one side thereof to form a side arm and being further extended 90 across said member to form a transverse arm and being bent inwardly to form a corresponding side arm which latter terminates at the inner end of the first named side arm, said transverse arm being centrally and 95 downwardly bowed, the free end of the other member being inclined downwardly and secured to the inner ends of said side arms, said free end being pointed and terminating below and in substantial alignment 100 with said transverse arm.

2. In a bottle cap remover, a handle formed of wire having one end bent to form a triangle and having its other end secured to the apex of the triangle and extending 110

beneath the base of the triangle and having a point which substantially aligns in a vertical plane with said base of the triangle.

3. In a bottle cap remover, a handle formed of wire having a lower part which is bent to form a triangle at its forward end and an upper part arranged in spaced parallel relation to the lower part, the forward end of which upper part is bent downwardly at an incline and is secured to the apex of the triangle and has a point at its free extremity which underlies the base of the triangle.
4. In a bottle cap remover, a handle

formed of wire having one end bent to form a transverse arm and having its other end secured to the body part of the handle above the arm to provide a finger grip and having its extremity pointed and extending below the arm.

In testimony whereof I have signed my name to this specification in the presence of two subscribing witnesses.

JOSEF SAVOIE.
